GEAR STRUCTURE

Harold S. Falk and Percy C. Day, Milwaukee, Wis.,
assignors to The Falk Corporation, Milwaukee,
Wis., a corporation of Wisconsin

Application May 15, 1933, Serial No. 671,124

4 Claims. (Cl. 74—439)

This invention relates to gear structures and particularly to the construction of relatively large gears.

An object of the present invention is to provide a relatively large, accurately centered, and accurately balanced gear, so constructed as to provide adequate strength and rigidity with minimum weight.

Large gears, several feet in diameter, are not uncommonly employed as propeller shaft drives in marine installations. Their size and rate of operation is such as to require accurate centering and accurate balancing, to effect a smooth gear action and avoid objectionable vibration, and, in order to facilitate maneuvering, it is highly desirable that the weight of such gears be reduced to a minimum consistent with strength and rigidity. In the gear of the present invention, all of these desirable characteristics are developed to a high degree.

Other objects and advantages will appear, expressed or implied, from the following description of a gear embodying the present invention.

The single figure of the accompanying drawing is a view, partly in section, and partly in elevation, of a large cast steel gear constructed in accordance with the present invention.

The gear shown is of the double helical type. It includes two concentric, axially spaced rims 10 of the same diameter, having oppositely inclined helical teeth cut therein. The rims 10 are connected through a rigid box like formation, including an intermediate, concentric, cylindrical web 11 of lesser diameter, having integral external end rings 12 which merge into the rims adjacent their inner edges. The gear is internally braced against distortion by a concentric substantially conical web 13, whose large end merges into the web 11, preferably at one end thereof, and which slopes inwardly therefrom into an end zone of the gear.

The gear is supported and centered primarily by a pair of end disks 14 and 15, closely fitted at their peripheries against accurately machined internal shoulders 16 and 17, formed adjacent the outer edges of the rims 10, and bored to seat upon machined shoulders 18 and 19, formed upon integral collars 20 and 21, provided on the shaft 22. The end disks are attached by bolting or otherwise to internal flanges 23 and 24, formed in the rims 10, and also to the shaft collars 20 and 21. The small end of the conical web 13 is also bored to seat snugly upon a machined shoulder 25 on the shaft collar 20 to which it is similarly attached.

It will thus be noted that a gear structure has been provided in which all of the parts may be of unusually thin, light weight design, without impairing the strength and rigidity of the gear structure, and in which both the internal and external surfaces of all of the parts are easily accessible and can thus be readily and accurately machined, by ordinary shop methods, to obtain any desired thinness of the several parts and to effect an accurately balanced gear.

In producing the gear shown, the rims 10, web 11, rings 12, and web 13 are cast in one integral piece in which all of the parts are of a thickness consistent with good foundry practice. The external and internal surfaces of the blank are then machined to greatly reduce the several parts to the desired thinness and to effect an accurately balanced gear blank, and the blank is finally assembled with the previously finished end disks 14 and 15 mounted upon the shaft 22, in the manner indicated.

Various changes may be made in the embodiment of the invention hereinabove specifically described without departing from or sacrificing the advantages of the invention as hereinafter claimed.

We claim:—

1. A large marine gear structure comprising the combination of a pair of concentric axially spaced rims having teeth formed thereon, an intermediate concentric web connecting said rims, and a concentric conical brace structure extending from said web toward an end zone of the gear, said rims, web, and brace structure comprising a one piece casting all of the internal surfaces of which are accessible for machining to reduce the thickness thereof and to balance the gear, together with a pair of end disks engaged with said rims adjacent their outer edges to support and center the same, and rigid mounting means for said disks and brace member.

2. A large marine gear structure comprising the combination of a pair of concentric axially spaced rims having teeth formed thereon, a concentric cylindrical web having external end rings connected with said rims adjacent the inner ends thereof, and a concentric conical web extending from an end of said cylindrical web into an end zone of the gear, said rims, rings, and webs comprising a one piece casting having internal surfaces accessible for machining to reduce the thickness thereof and to balance the gear, together with a pair of disks engaged within said rims to support and center the same, and a

shaft on which said disks and conical web are mounted and secured.

3. A large marine gear blank comprising a pair of concentric axially spaced tooth carrying rims, a concentric web structure within said rims and having a tapered end, and spaced rings connecting said web structure with said rims, said rims, rings, and web structure comprising a one piece casting all of the internal surfaces of which are accessible for machining to reduce the thickness of said parts and to balance the gear.

4. A large marine gear comprising the combination of an axially extended rim structure having two series of oppositely inclined helical gear

teeth cut therein, an internal brace structure cast integral with said rim structure, and including an integral conical web coaxially disposed within said rim structure and extending into an end zone thereof, the surfaces of said rim and brace structure being machined to reduce the thickness thereof and to accurately balance the gear, supporting disks attached to the ends of said rim structure, and means rigidly connecting said disks and brace member to support and brace the gear.
